PROTECTIVE CLOSURE

Charles A. Scheeler, Buffalo, N. Y., assignor to
 Buffalo Wire Works Co., Inc., Buffalo, N. Y., a
 corporation of New York

Application October 14, 1931. Serial No. 568,764

4 Claims. (Cl. 20—1.01)

- This invention relates to a protective closure for a passage in a partition between the office of a bank teller or the like on one side of a wall or partition and the reception room of the public on the other side thereof so that money and valuables can be safely passed through said passage from one party to the other without exposing the cashier to the danger of being shot or otherwise injured by bandits in attempting to hold up the bank.
- 10 It is the object of this invention to provide a closure of this character which is simple and compact in construction, and which can be readily and easily operated for transferring money and valuables through the opening in the partition and yet protect the cashier against possible injury if attacked by criminals intending to rob the bank.
- In the accompanying drawings:
- Fig. 1 is a front elevation of the protective closure embodying my invention.
- 20 Fig. 2 is a side elevation thereof and showing in section the partition or wall in which the closure is mounted.
- Fig. 3 is a top plan of the same.
- Fig. 4 is a vertical transverse section of the same taken on line 4—4, Fig. 3.
- 25 Fig. 5 is a vertical longitudinal section of the same taken on line 5—5, Fig. 3.
- Fig. 6 is a horizontal section taken on line 6—6, Fig. 1.
- 30 In the following description similar characters of reference indicate like parts in the several figures of the drawings.
- The numeral 10 represents the wall or partition of a building on the inner side of which is arranged the desk or office of a bank teller, or other officer and on the opposite side of which is located a reception room for the use of the public and in this wall is arranged an opening or window 11 through which moneys, documents and other valuables may be exchanged between the public and said official as commonly done in banks or similar institutions. The protective closure embodying the present invention for the purpose of permitting an exchange of valuables through this opening between the public on one side of this partition and the official on the other side of the same and still safeguarding the official against possible attack by shooting or otherwise by bandits from the public side of the partition is preferably constructed as follows:
- Within the opening 11 in the partition is arranged a frame which preferably consists of upper and lower horizontal angle irons or bars 12, 13 and two upright side angle irons or bars 14, 15 which connect corresponding ends of the upper and lower bars, said bars forming together a rectangular frame so that the rear flanges of these bars are arranged within the opening 11 while the front flanges thereof engage with the front or public side of the partition and are secured thereto by any suitable means for instance by means of bolts 16, as shown in Figs. 2, 3, 5 and 6. In order to finish off the front side of this frame the same may be provided with a molding or finishing strip 17 of rectangular form which is applied to the front side of the same around the opening therein, as best shown in Figs. 5 and 6.
- Projecting rearwardly and laterally from the rear flanges of the upright bars 14, 15 of the window frame are two upright side walls of a housing each of which comprises a curved body 18 and a front flange 19 arranged at the vertical front edge of this wall and secured to the outer side of the vertical flange of the respective frame side bar 14 or 15 by means of bolts 20. These two side walls of the housing are spaced apart and have their concave sides opposed to each other and preferably arranged concentrically relatively to each other and also concentrically with reference to a turret which is arranged 60 within this housing as will be described later on. At its rear edge each of the housing side walls 18 is provided with a forwardly projecting upright channel 21 which is formed thereon by curling or bending the rear edge portion of each of these side walls inwardly and forwardly relatively to the turret axis the requisite extent. At its lower edge each of the housing side walls 18 is provided with a horizontal flange 22 which extends inwardly toward the axis of the turret and which is arranged between these housing side walls, and on the upper edge of each of the housing side walls the same is provided with a similar horizontal flange 23 which also projects inwardly toward the axis of the turret. Each of the side 65 walls of the housing together with its front attaching flange 19, rear channel 21 and lower and upper flanges 22 and 23 are constructed of sheet steel or other strong and durable material which is bullet-proof or highly resistant against the penetration by bullets which may be fired against the same by fire arms in the hands of bandits who may be attempting to hold up the cashier and rob the bank.
- Projecting rearwardly from the rear flange of the lower bar of the window frame is a supporting arm 24 of sheet metal which is secured at its front end to the rear flange of each lower frame bar by means of bolts 25 or other suitable means, and projecting rearwardly from the rear flange 70
- 114

of the upper window frame bar 12 is another horizontal supporting arm 26 of metal which is secured at its front end to the respective rear flange of the upper window bar 12 by bolts 27, 5 as shown, or other suitable means.

In the space between the side walls 18 and the lower and upper flanges 22 and 23 of the housing and the lower and upper supporting arms 24 and 26 is arranged a turret which is so constructed that persons located on the opposite sides of the building partition are able to pass monies, papers, documents or other valuables back and forth through the window in the partition without at any time exposing the person in rear of the partition to possible danger of being shot by anyone located in front of the partition. This turret in its preferred form is constructed as follows:

The numeral 28 represents a lower horizontal metal disk, preferably of circular form which is arranged between the housing side walls 18 and the front flange 19 and rear channel 21 thereof and above the lower supporting arm 24, the lower housing flanges 22 and the rear flange of the lower window frame 13. The lower housing disk 28 is provided centrally with a downwardly projecting pivot pin 29 which is journaled in a bearing opening 30 in the rear part of the lower supporting arm 24, as best shown in Figs. 4 and 5. The numeral 31 represents an upper head of metal constructed preferably in the shape of a circular disk and arranged between the upper parts of the housing side walls 18, the front flanges 19 and rear channels 21 thereof and underneath the rear flange of the upper window bar 12 and the upper supporting arm 26. This upper disk 31 is provided with an upwardly projecting pivot pin 32 which is journaled in a bearing opening 33 formed in the central part of the upper supporting arm 26. Extending diametrically across the central part of the space between the lower and upper heads 28 and 31 of the turret is a partition which preferably consists of two plates 34 of sheet metal which are arranged side by side and secured at their upper and lower edges to the adjacent surfaces of the turret heads 28 and 31 by means of spot welding or any other suitable means. At opposite ends of this partition the turret is provided with two side walls each of which preferably consists of two sheet metal plates 35, 35 which are formed integrally with the partition plates 34, 34, respectively, and project laterally therefrom in opposite directions from the corresponding edges thereof and are secured at their lower and upper ends to the lower and upper heads of the turret by spot welding or otherwise. By this means two compartments or chambers 36, 37 are formed 60 on the turret which are arranged diametrically opposite each other and have their open sides facing outwardly toward the periphery of the turret. The side walls of the turret are arranged tangentially with reference to the axis of the turret so as to form pockets 38 in the opposite sides of these turret side walls and the peripheral edges of the heads of the same. Within each of these pockets two cleats or stiffening bars 9 of angular form are arranged and secured to the outer sides of the edge portions of the side wall sections 35 and also the adjacent peripheral portions of the lower and upper heads of the turret by means of spot welding or the like. The lower and upper heads, diametrical partition, the side walls and the reinforcing cleats of the tur-

ret are all preferably constructed of sheet steel or other material which is practically proof against perforation by bullets which are fired from a revolver or other firearm. This turret may be turned by the cashier or other person on the rear or inner side of the partition by means of a handle 39 applied to the upper end of the upper pivot pin 32.

Locking means are provided for holding the turret against turning when one of its chambers 85 opens fully toward the window opening and the other opens fully toward the cashier space on the inner side of the building partition or wall which locking means are so constructed that they are only releasable from the inner side of the building wall and thereby prevent rotation of the turret by anyone from the front or outer side of this building wall. Although these locking means may be of any suitable construction the same are preferably constructed as follows: 95

The numerals 40, 41 represent two locking openings which are formed in the upper head 31 of the turret on diametrically opposite sides of the axis thereof and 42 represents a locking pin 5 or catch which is mounted on the housing and 100 adapted to releasably engage one or the other of these locking openings for the purpose of either holding the turret against turning or to permit the same to be turned at will. This locking pin 42 is guided in an opening 43 formed in the rear 105 end of the upper supporting arm 26 and is mounted on the central part of a shifting arm 44 which is preferably constructed of a strip of spring metal which is arranged above the rear part of the upper supporting arm 26 and has its front 110 end secured thereto by means of rivets 45 or the like while its rear end is provided with a handle 46 whereby this shifting arm may be manipulated.

For the purpose of retaining the two sections of 115 the housing on opposite sides of the turret in their proper position relative to each other and to the turret a transverse brace 47 of metal is preferably employed which extends over the upper head of the turret and the adjacent part of the upper 120 supporting arm 26 and is secured at its opposite ends to the upper flanges 23 of the housing side walls by means of screws 48, as shown in Fig. 3, or by means of other suitable fastenings. 125

In the position of the parts shown in Fig. 5 the shifting arm 44 is depressed due to its resilience so that the locking pin 42 is engaged with the rear locking opening 40 in the turret whereby the latter is held against turning. If it is desired to rotate the turret the officer on the inner side of the building partition 10 raises the shifting arm 44 by means of the handle 46 a sufficient extent to disengage the locking pin 42 from the opening 40 whereupon the turret may be rotated by means of the handle 39 so as to reverse the position of the chambers or compartments 36 and 37 and after such reversal releasing of the shifting arm 44 will cause the resilience of the same to engage the locking pin 42 with the other locking 130 opening 41 and again hold the turret against 135 turning.

While the turret is thus locked persons on the front side of the partition may deposit money, 145 papers, documents or other valuables in the forwardly opening compartment which after turning the turret for rapid revolution will be transferred to the cashier on the rear side of the building partition; and money, papers or other valuables may in like manner be deposited in the in- 150

wardly opening compartment of the partition and transferred from the inner side of the turret to the outer side of the same which faces the window in the building wall for removal by the 5 person on the front side of this partition.

While the turret is in a position in which one of its transfer chambers faces fully forwardly and the other fully rearwardly, then the upper and lower heads, side walls and diametrical partition of the turret form a complete obstruction 10 against the passage of any bullets which may be fired through the window toward the cashier, thereby preventing the latter from being injured by bandits.

15 If a bandit attempting to hold up the bank should fire a bullet from the outer side of the building partition into the space between the turret and either side wall of the housing for the purpose of injuring the cashier and holding 20 up the bank such bullet would glance off from the concave inner side of the respective housing side wall and enter the vertical gutter 21 of the respective side wall and be directed by the latter upwardly or downwardly toward the upper 25 or lower flange of the respective housing side wall and thereby prevent it from striking the cashier and injuring him.

It will now be clear that by means of this protective closure valuables can be transferred 30 through the cashier window in the building wall from the public to the private side of the same without liability of the cashier on the private side of the partition being injured by bullets fired through the window in attempting to hold up the 35 bank.

I claim as my invention:

1. A protective closure for an opening in a 40 building wall comprising a housing arranged opposite said opening and having a passage, and a turret pivoted to turn about a vertical axis and having an upper head, a lower head, two side walls arranged between said heads, and a partition between said walls and forming with the side walls and heads two outwardly opening chambers on diametrically opposite sides of the turret which

may be selectively exposed on either side of said 80 turret said partition consisting of two plates arranged side by side and each of said side walls consisting of plates extending laterally in opposite directions from the corresponding ends of two partition plates.

2. A protective closure for an opening in a building wall comprising a housing arranged opposite 85 said opening and having a passage, and a turret pivoted to turn about a vertical axis and having an upper head, a lower head, two side walls arranged between said heads, and a partition between said walls and forming with the side walls and heads two outwardly opening chambers on diametrically opposite sides of the turret which may be selectively exposed on either side of said 90 turret said partition consisting of two plates arranged side by side and each of said side walls consisting of plates extending laterally in opposite directions from the corresponding ends of two partition plates and cleats secured to the outer sides of said turret side walls at opposite ends thereof.

3. A protective closure for an opening in a wall 100 comprising a housing having a frame arranged in said opening and two guard walls projecting laterally from opposite vertical sides of said frame, and a turret pivotally supported on said housing between the guard walls thereof and having oppositely opening chambers said guard 105 walls being curved concentrically with the axis of said turret and provided at their corresponding outer ends with inwardly turned catch channels.

4. A protective closure for an opening in a wall 110 comprising a housing having a frame arranged in said opening and two guard walls projecting laterally from opposite vertical sides of said frame, and a turret pivotally supported on said housing between the guard walls thereof and having oppositely opening chambers said guard 115 walls being curved concentrically with the axis of said turret and provided at their upper and lower ends with inwardly projecting flanges which overlap the upper and lower ends of the turret.
